UNITED STATES PATENT OFFICE.

HORACE G. JOHNSTON, OF CORTICANA, TEXAS.

PIPE-TONGS.

1,017,552.

Specification of Letters Patent.

Patented Feb. 13, 1912.

Application filed April 29, 1911. Serial No. 624,098.

To all whom it may concern:

Be it known that I, HORACE G. JOHNSTON, a citizen of the United States, residing at Corsicana, in the county of Navarro and 5 State of Texas, have invented certain new and useful Improvements in Pipe-Tongs; and I do hereby declare the following to be a full, clear, and exact description of the invention, such as will enable others skilled in 10 the art to which it appertains to make and use the same.

This invention relates to rotary well boring machinery and has for an object to provide an apparatus for use in conjunction 15 with the rotary machines especially a rotary such as is described in applicant's Patent No. 959,351, issued May 24th, 1910 and when applied thereto for uncoupling casing tubes and other well pipes employed.

20 A further object of the invention is to provide a pipe tong adapted to be carried upon and used by a rotary machine such as described in said patent of such construction that it may remain upon and in association 25 with said machine when not in actual use and in position to be quickly and readily moved or swung into position for operation when desired.

30 A further object of the invention is to provide an improved pipe tong adapted to be pivotally mounted upon uprights carried upon the base of a rotary machine and also upon the rotary table to be used in conjunction for unscrewing or disconnecting pipe 35 sections.

With these and other objects in view the invention comprises certain novel constructions, combinations and arrangement of parts as will be hereinafter more fully 40 described and claimed.

In the drawings, the figure is a perspective view of a rotary machine provided with uprights and with the improved pipe tong applied thereto.

45 Like characters of reference designate corresponding parts throughout the several views.

The rotary machine used in association 50 with this pipe tong is substantially like that described in the said Patent No. 959,351 embodying the base 10 and rotating table 11 upon the former of which is erected an upright 13 by being inserted in one of the 55 sockets 14 while the rotary table is provided with one or more uprights 15 likewise in-

serted in one of the sockets 16. With the exception of a hook or crook at the upper end of one of the uprights the device described is similar in all respects to that disclosed in said patent. The improved pipe 60 tong which forms the subject matter of this application is adapted for use in association with said rotary and comprises a link member 17 having a hole or opening 18 adapted to slip over and fit upon either of the uprights 13 or 15 as may be found desirable; 65 two of such pipe tongs being employed with each "rig".

To the link member 17 a lever member 19 is pivoted as at 20 and free to swing upon 70 said link member which may also if desired swing about the uprights 13 and 15. The principal use of the link 17 is to permit such swinging movement of the lever 19 and also to accommodate a difference in length between the uprights and the pipe under varying conditions. The lever 19 is provided at its end opposite the pivot 20 with a serrated face 21 while a jaw member 22 is pivoted to said lever as at 23 to grip the pipe in the 80 usual well known manner. The formation of the hook shaped jaw member 22 and the serrated face 21 and their co-action will be so apparent as to require no further explanation or disclosure. 85

In use two of the tongs are mounted upon the uprights of the base and the rotating table respectively as shown at Fig. 1 and the rotating table started in the usual manner. Such starting of the rotary table moves the 90 tong which is connected thereto and carried thereby and moves therewith the section of the pipe or the section of the coupling which it is gripping. The other tong which is held rigidly by attachment to the upright of the base holds the other pipe section against rotation whereby the continued movement of the rotary table unscrews the parts. When the parts have been disconnected the tongs are readily and easily disconnected from the 95 pipe or from the coupling to which they are connected and are swung around out of operative position either by swinging upon the pivots 20 or upon the uprights 13 or 15.

In the drilling of large wells where the casing is oftentimes from ten to fourteen inches the pipe tongs employed become of necessity very large and very heavy under ordinary conditions requiring several men to lift and place upon the pipe sections. 110

With the device as shown the tongs remain constantly in position and may be swung into operative relation with the pipe and connected up easily, quickly and readily by 5 one man and without requiring a great degree of strength. The saving of time is also a very important element.

I claim:

1. The combination with a rotary well 10 drilling machine comprising a stationary base and rotating table with uprights up- standing from each, of collars surrounding the uprights and pipe tongs pivoted to the collars in such manner as to be supported

by the collars and uprights in horizontal po- 15 sition.

2. The combination with an upright, of a collar surrounding and rotatable upon the upright, and pipe tongs pivoted to the collar and capable of movement in a horizontal 20 plane about the upright.

In testimony whereof I affix my signature in presence of two witnesses.

HORACE G. JOHNSTON.
